PIVOTED LOAD LIFTING MECHANISM

Morris R. Elliott, Robert Lapsley, and George L. Turner, Buchanan, Mich., assignors to Clark Equipment Company, Buchanan, Mich., a corporation of Michigan

Application July 7, 1950, Serial No. 172,576

10 Claims. (Cl. 280—44)

1

Our invention relates generally to self-propelled hand lift trucks, and, more specifically, is directed to a pivoted load lifting mechanism for hand lift trucks.

One form of hand operated lift truck, known in the art, comprises a main frame which is supported by a wheel unit. Disposed forwardly of the main frame is a load supporting means which is supported at its forward end by means of extensible wheel assemblies. The load supporting means is mounted, for vertical movement, on the main frame by means of vertical slides and roller members, respectively mounted to the main frame and load supporting means. Vertical movement of the load supporting means, with respect to the main frame, is effected by means of load elevating means, as, for example, one or more hydraulic piston and cylinder assemblies carried by the main frame. The hydraulic piston and cylinder assemblies are operatively connected, through suitable linkage means, to the extensible wheel assemblies for extending and retracting the latter, and thereby elevating and lowering the load supporting means which, as aforescribed, is guided on the main frame by means of the vertical slides and roller members. This form of load elevating means has proved unsatisfactory as a load, carried by the load supporting means, is inadequately supported at the inner end of the load supporting means adjacent the guide means.

It is an object of our present invention to provide a load lifting mechanism for a hand lift truck which will elevate and lower the inner and outer ends of the load supporting means simultaneously.

We propose to accomplish this object by providing load supporting means which is pivotally mounted intermediate its ends to the the outer end of horizontal forwardly extending frame means carried by the main frame of a hand lift truck. The main frame is supported on a wheel unit, and the forward end of the load supporting means is supported on a pair of extensible wheel assemblies which are extended and retracted through suitable linkage means, preferably actuated by means of a pair of hydraulic piston and cylinder assemblies carried by the main frame. A pair of bell cranks are pivotally mounted to the main frame and at their one ends extend through openings formed in the frame means and engage the under surface of the load supporting means adjacent the rear end thereof. The bell cranks, at their other ends, have suitable connection with the afore-

55

described hydraulic piston and cylinder assemblies. When the piston and cylinder assemblies are suitably energized the extensible wheel assemblies are caused to be extended and the bell cranks rotated to elevate the load supporting means, while the main frame pivots about the connection between the load supporting means and the outer end of the horizontally extending frame means carried by the main frame. It will thus be realized that since the load supporting means is elevated at its inner and outer ends simultaneously, a load carried thereon is supported in a superior manner than has heretofore been possible.

It is another object of our present invention to provide a pivoted load lifting mechanism, of the character described, which is of sturdy construction and light in weight, and which is efficient in operation and economical to manufacture.

The specific form of hand lift truck with which the load elevating mechanism of our present invention is shown embodied is described and claimed in the copending application of Boylan and Turner, Serial No. 170,828, filed June 28, 1950. It will be understood that the load elevating mechanism of our invention may be incorporated with other forms of hand lift trucks.

Now, in order to acquaint those skilled in the art with the manner of constructing and using the device of our present invention, we shall describe in connection with the accompanying drawings a preferred embodiment of our invention.

In the drawings:

Figure 1 is a side elevational view of the hand truck of our present invention with portions being broken away for sake of clarity;

Figure 2 is a plan view of the hand truck of Figure 1;

Figure 3 is a diagrammatic view of the hand truck of Figure 1, with the load supporting means in a normal position; and

Figure 4 is a diagrammatic view of the hand truck of Figure 1, with the load supporting means in an elevated position.

Referring now to Figures 1 and 2, there is shown a hand truck, indicated generally by the reference numeral 10, having a horizontally extending main frame 11 to which, at the forward edge thereof, is secured the upper edge of a vertically downwardly extending plate member 12. Secured to the vertical plate member 12 and projecting forwardly therefrom, adjacent each side thereof, are a pair of load supporting frames 13.

Each of the load supporting frames 13 is provided with a pair of horizontally spaced apart bracket members 14 suitably secured, as by welding, to the lower edge thereof. A pair of housing members 24 and 25 are mounted on the main frame 11 and are, respectively, provided for enclosing the hydraulic fluid system which controls the load elevating mechanism, to be described hereinafter, and the batteries (not shown) which supply power to the electric motor, to be described hereinafter.

Secured to the underside of the horizontal main frame 11 is a race member 16 which is supported upon a plurality of ball members 17 carried by a lower race member 18. A retaining ring 9 is secured to the underside of the race member 16 and cooperates with an annular flange extending radially from the race member 18 for positioning the latter relative to the race member 16. The lower race member 18 is secured to a rotatable horizontally extending ring member 19, to which, at each side thereof, is secured a depending plate member 20. Rotatably mounted within the depending plate members 20, intermediate thereof, is a motor-in-wheel construction, indicated generally by the reference numeral 21, which is fully described in the copending application of Hawkins, Lapsley, and Turner, Serial No. 175,376, filed July 22, 1950. The motor-in-wheel construction 21 comprises an electric motor casing 22 upon which is mounted, for rotation therewith, a tire 23. The horizontal rotatable ring member 19, the depending plate members 20, and the motor-in-wheel construction 21, are adapted to rotate as a unit about a vertical axis and thus the motor-in-wheel construction 21 may be utilized both for powering and steering the hand truck of our present invention.

A shaft 51 is rotatably supported within a pair of vertically extending spaced apart plate members 52 which are suitably secured to the rotatable frame 19 of the hand truck 10. Mounted on the shaft 51 between the plate members 52 is the lower end of a tubular steering handle 54. For a more detailed description of the mounting of the steering handle 54 to the rotatable frame 19 reference may be had to the aforementioned copending application of Boylen and Turner. Mounted to the upper end of the steering handle 54, as shown in Figure 1, is a steering head 55 which has mounted adjacent each side thereof a pair of coaxially aligned laterally projecting hand grips 56. Mounted across the top of the steering head 55 is an inverted U-shaped hand guard 57. Conveniently disposed about the steering head 55 are a plurality of operating buttons 58 which are adapted to be manipulated for starting and stopping the truck 10, and for operating the various hydraulic devices associated therewith. Control lines, connecting the operating buttons 58 with the various hydraulic devices and the prime mover of the truck 10, are disposed within the tubular steering handle 54.

Pivots mounted, intermediate of their ends, by bolts 63, to the outer ends of the bracket members 14, secured to the lower edge of the horizontal frame members 13, are a pair of forwardly projecting fork frames 64 which are formed with aprons around their outer edges. Interconnecting the inner ends of the fork frames 64 is a transverse vertically extending plate member 65 which has flange members 66 formed integrally along each vertical edge, which flange members are adapted to be disposed or wrapped around the vertical edges of the plate member 12 carried by the main frame 11 of the hand truck 10.

Disposed adjacent each side of the hand truck 10 is a load elevating mechanism, indicated generally by the reference numeral 62, which is adapted to cooperate with each of the fork frames 64. Since both of the load elevating mechanisms 62 are of the same construction, and operate in the same manner, it is believed that a description of one will be sufficient for purposes of the present disclosure.

10 Pivots mounted to a shaft 67, secured at its ends within the apron of the fork frame 64, adjacent the forward end thereof, is a pair of spaced bracket members 68 which, at their outer ends, are spread laterally. Journalled in the outer ends 15 of the bracket members 68 is a shaft 69 upon which is mounted a pair of rollers 70. When the bracket members 68 are rotated clockwise about the shaft 67 the rollers 70 are forced downwardly, which provides a reaction point for forcing the fork frames 64 upwardly. A transverse slot 71 is provided in the upper surface of the fork frame 64 for receiving the upper peripheries of the roller members 70 when the fork frame 64 is in a non-elevated position. A second transverse slot 94 is provided in the upper surface of the fork frame 64 for receiving the one ends of the brackets 68.

20 Mounted, adjacent its ends, to the bracket members 68 is a shaft 73 upon which is pivotally mounted the ends of a fork member 74. Rotatably mounted on the shaft 73, between the ends 30 of the fork member 74, is a roller member 75. The fork member 74 is suitably secured to the one end of a draw rod 76, which draw rod 76, at its other end, is secured to a T-shaped member 77. 35 Pivots mounted, by a pin member 93, to the ends of the T-shaped member 77 are a pair of parallel links 78 which, at their other ends, are pivotally mounted, as by pin member 79, to the one leg of a bell crank 80. The bell crank 80 is pivotally mounted about a fixed shaft 81 carried by bracket 72 secured to the rear surface of the plate member 12. The other leg of the bell crank 80 is pivotally mounted, as by a pin member 82, to the lower end of a piston rod 100 of a hydraulic piston and cylinder assembly, indicated generally by the reference numeral 84, which hydraulic assembly 84, at its upper closed end, is pivotally mounted, by a pin member 85, to a vertical flange member 86 secured to the lower surface of the main frame 11 of the hand truck 10.

40 Pivots mounted to the vertical plate member 12 is a bell crank 87 which, at its forward end, is provided with a fork member 88, between the legs of which extends a shaft 90 upon which is rotatably mounted a roller 89. The roller 89 is adapted 45 to extend through a slot formed in the frame member 13 so as to engage the lower surface of the fork frame 64. The other end of the bell crank 87 is pivotally mounted, by a pin 91, to the lower end of a connecting link 83 pivotally mounted at its upper end about pin 82 to the piston rod 100.

50 The hydraulic piston and cylinder assemblies are connected through suitable fluid lines (not shown) to a conventional fluid pump (not shown) 55 carried by the main frame 11.

When fluid under pressure is admitted to the upper end of the hydraulic piston and cylinder assembly 84, the piston rod 100 and connecting link 83 are extended causing the bell crank 80 to rotate clockwise about the pin 81 and the bell crank 87 to rotate counterclockwise about the pin member 92. Counterclockwise rotation of the bell crank 87 urges the inner end of fork frame 64 upwardly. Clockwise rotation of the bell 70 crank 80 causes the link members 78 to pull the 75

draw rod 16 to the left, as viewed in Figure 1, thereby causing the bracket members 68 to be rotated clockwise about the shaft 67 which urges the outer ends of the fork frames 64 upwardly. Therefore, it will be realized that the fork frames 64 are raised adjacent their inner ends by means of the bell cranks 87 and at their outer ends by means of the bracket members 68 and the rollers 70.

When the fork frames 64 are in their non-elevated position the main frame 11 and the fork frames 64 assume the position shown in Figure 3. Upon admission of fluid under pressure to the hydraulic piston and cylinder assemblies 84, the inner and outer ends of the fork frames 64 are raised simultaneously to the position shown in Figure 4, and the main frame 11, plate member 12, and frames 13 are rotated counterclockwise with respect to the fork frames 64 about the pin members 63 until they assume the position shown in Figure 4.

When fluid under pressure is bled from the hydraulic piston and cylinder assembly 84, the piston rod 100 and connecting link 83 are caused to move upwardly, thereby rotating the bell crank 80 counterclockwise about pin member 81 and the bell crank 87 clockwise about pin member 92. This movement of the bell cranks 80 and 87 lowers the fork frames 64.

It will be noted that the hydraulic piston and cylinder assemblies 84, which are utilized for actuating the elevating mechanisms of the fork frames 64, are disposed below the main frame 11, rearwardly of the vertical transverse plate member 65 which comprises part of the load supporting means of our present invention. By disposing the hydraulic piston and cylinder assemblies 84 rearwardly of the plate member 64, adjacent each side thereof, the main support wheel 23 is permitted to be disposed closely adjacent the load supporting means, and thus the weight of a load supported on the fork frames 64 is distributed better throughout the length of the truck.

While we have shown and described what we believe to be a preferred embodiment of our invention, it will be understood that various modifications and arrangements may be made therein without departing from the spirit and scope of our present invention.

We claim:

1. In an industrial truck, the combination of a wheel unit, a main frame mounted on said wheel unit, load supporting means pivotally mounted to said main frame about a single axis extending transversely thereof, extensible ground engaging means for supporting the forward end of said load supporting means, a lever pivotally mounted to said main frame with one end engaging the underside of said load supporting means, actuating means for extending said extensible ground engaging means, and said actuating means having connection with said lever whereby when said actuating means is energized said ground engaging means is extended and said end of said lever engaging said load supporting means is urged upwardly thereby elevating said load supporting means while said main frame is pivoted with respect to the latter.

2. In an industrial truck, the combination of a main frame including a forwardly extending portion, a wheel unit for supporting said main frame, load supporting means pivotally mounted adjacent the outer end of said forwardly extending portion about a single axis extending transversely thereof, extensible ground engaging means for

supporting the forward end of said load supporting means, a lever pivotally mounted to said main frame with one end engaging the underside of said load supporting means, actuating means for extending said extensible ground engaging means, and said actuating means having connection with said lever whereby when said actuating means is energized said ground engaging means is extended and said end of said lever engaging said load supporting means is urged upwardly thereby elevating said load supporting means while said main frame is pivoted with respect to the latter.

3. In an industrial truck, the combination of a main frame including a forwardly extending portion, a wheel unit for supporting said main frame, load supporting means pivotally mounted intermediate its ends adjacent the outer end of said forwardly extending portion about an axis extending transversely thereof, ground engaging means for supporting the forward end of said load supporting means, and means between said main frame and said load supporting means for pivoting the former with respect to the latter whereby said load supporting means is elevated.

4. In an industrial truck, the combination of a main frame including a pair of forwardly extending frame members, a pair of forwardly extending fork frames pivotally mounted intermediate their ends adjacent the outer ends of the adjacent frame members about an axis extending transversely thereof, ground engaging means for supporting the forward ends of said fork frames, and means between said frame and at least one of said fork frames for pivoting the former with respect to the latter whereby said load supporting means is elevated.

5. In an industrial truck, the combination of a main frame including a pair of forwardly horizontally extending frame members, a wheel unit for supporting said main frame, a pair of forwardly extending fork frames pivotally mounted intermediate their ends to the outer ends of the adjacent frame members about an axis extending transversely thereof, extensible ground engaging means mounted adjacent the forward ends of each of said fork frames, and means between said main frame and said ground engaging means for extending and retracting the latter whereby said main frame is pivoted with respect to said fork frames and said fork frames are thereby elevated.

6. The combination of claim 5 wherein said ground engaging means comprises wheel units pivotally mounted about transverse axes to said fork frames.

7. The combination of claim 6 wherein said ground engaging means are extended by means of rectilinearly movable draw rods actuated by means of hydraulic piston and cylinder assemblies.

8. The combination of claim 5 including slots formed in said horizontal frame members, a pair of levers pivotally mounted to said main frame having ends extending through said slots into engagement with the lower surfaces of said fork frames, and means for rotating said levers whereby said fork frames are elevated and lowered.

9. The combination of claim 5 wherein said ground engaging means comprises wheel assemblies pivotally mounted about transverse axes to the outer ends of said fork frames, a pair of draw rods having connection adjacent their one ends to said wheel assemblies, actuating means for effecting rectilinear movement of said draw rods, slots formed in said horizontal frame members, a

pair of levers having connection adjacent their one ends to said actuating means and at their other ends extending through said slots in said horizontal frame members for engagement with the lower surfaces of said fork frames, whereby when said actuating means are energized said wheel assemblies are extended and said ends of said levers engaging said fork frames are urged upwardly thereby elevating said fork frames while said main frame is pivoted with respect to the latter.

10. In an industrial truck, the combination of a main frame including a pair of horizontal forwardly extending frame members, a wheel unit for supporting said main frame, a pair of fork frames pivotally mounted intermediate their ends to the outer ends of the adjacent frame members, auxiliary wheel units pivotally mounted adjacent the outer ends of said fork frames, load elevating means associated with at least one of said fork frames comprising, a draw rod connected adjacent its one end to one of said auxiliary wheel units, a pair of first levers having connection adjacent their one ends with the other end of said draw rod, a slot formed in the surface of the 25

adjacent horizontal frame member, a bell crank pivotally mounted to said main frame, the one end of said bell crank being disposed through said slot in said horizontal frame member into engagement with the lower surface of said fork frame, means between the other ends of said levers and bell crank for effecting movement thereof whereby when said auxiliary wheel unit is extended and said one end of said bell crank is urged upwardly said fork frame is elevated while said main frame is pivoted with respect to the latter.
